CLAIM

The ornamental design for a blood glucose meter as shown and described.

DESCRIPTION

1. Blood glucose meter

1.1 : Perspective

1.2 : Front

1.3 : Back

1.4 : Left

1.5 : Right

1.6 : Top

1.7 : Bottom

This design features a portable blood glucose meter made of synthetic resin or metal material; it is specifically designed for measuring blood glucose levels and is intended to be used in conjunction with a mobile application installed on a portable device such as a smartphone; when a blood sample is inserted into the blood sample inlet located at the front, the blood glucose level is displayed on the display unit; the blood glucose meter allows users to measure their blood glucose levels conveniently and effectively.
